DEVICE FOR VARYING CURVATURE OF BOAT KEELS

Filed Oct. 14, 1947

LOREN P. BURCH

BY

Loren P. Burch

ATTORNEY

the invention relates to a device for aligning the keel of a boat, which device is operable during operation of the boat, for adjusting the alignment of the flat portion of the keel relative to a straight line which is identified in Figure 1 by a broken line A.

UNITED STATES PATENT OFFICE

Patent No. 2,612,129
Issued August 5, 1952
For a

DEVICE FOR VARYING CURVATURE OF BOAT KEELS

Loren P. Burch, Aberdeen, Wash.

Application October 14, 1947, Serial No. 779,769

2 Claims. (Cl. 114—0.5)

1

This invention relates to boats and is particularly related to the keel of the boat.

The primary object of the invention is to be able to raise or lower the keel midway the stern and bow.

In boat language if the keel is raised above a straight line drawn from the stern to the bow it is known as placing a hog in the keel. When the keel is lowered midway the bow and the stern beyond the straight line, it is known as placing a rocker in the keel. With a hog in the keel the bow of the boat tends to remain near the water while if a rocker is put in the keel the bow of the boat tends to rise above the water line.

It is very desirable to have the bow of the boat rise above the water line for high speed operation and it is somewhat desirable to have the bow of the boat remain on the water line while operating with low power.

With my new and improved device for aligning keels of boats the keel can be aligned while the boat is being propelled through the water, which is a most desirable advantage.

A further object of the invention is that during the life of a boat the alignment of the keel changes and with my new device this deformation can be corrected at will.

These and other incidental objects will be apparent in the drawings, specification and claims.

Referring to the drawings:

Figure 1 is a side view of a conventional boat having my new and improved device installed therein for aligning the keel.

Figure 2 is a sectional view of the boat, taken on line 2—2 of Figure 1, more clearly illustrating my new and improved keel aligning device.

Figure 3 is a detail fragmentary view taken on line 3—3 of Figure 2.

Figure 4 is a modified form of construction adapted to certain types of boats.

Referring now to the drawing, the present invention is concerned with a boat which typically comprises a bottom 2 with a longitudinally extending centrally disposed keel 1 and having side walls 5 extending up to gunwales 6. The keel 1 extends from the bow 3 to the stern 4 of the boat, and except for a short length which is curved up to form the bow 3, the main length of the keel is normally substantially flat and substantially parallel and aligned with a straight line which is identified in Figure 1 by a broken line A.

The present invention resides in means which is operable during operation of the boat, for adjusting the alignment of the flat portion of the keel 1 relative to the line A. Normally, the keel

1 is aligned with the line A but in some circumstances it is desirable to have the keel bowed upwardly so that the central portion of the keel is raised as high as the level of the broken line B, which is known as hogging the keel. In other circumstances, it is desirable to bow the keel downwardly so that the central portion is lowered to the level of the broken line C, which is known as putting a rocker in the keel.

The selective alignment of the keel is accomplished, in accordance with the present invention, by means of an athwartship bridge spanning the boat and an adjustable member, specifically a screw device, connected between said bridge and the keel substantially midway of the flat portion of the keel. As shown in Figures 1—3, a bridge 12 may be mounted athwartship on the gunwales 6 to span the boat, this bridge being substantially centrally of the boat. A turnbuckle screw is connected between the keel 1 and the bridge 12, this screw comprising a turnbuckle 14 threadedly engaging two bolts 7 and 10. The bolt 7 is connected to the keel 1, said bolt preferably extending through the keel with its head 9 embedded in the keel and the bolt clamped by a nut 8. The bolt 10 is connected to the bridge 12 by means of a block 11 mounted on the bridge, the bolt 10 extending through the block 11 and being clamped by a nut 13.

Thus, to adjust the alignment of the keel 1, the turnbuckle screw is selectively adjusted to be shortened or lengthened, this adjustment being accomplished by merely turning the turnbuckle 14 to thread it relative to the two bolts 7 and 10.

The turnbuckle 14 is adjusted by the operator of the boat and this adjustment may be effected while the boat is being propelled through the water. This is the outstanding feature of my invention, the ability to make the adjustment of the keel while the boat is being propelled, as this will give the desired result in the operation of the boat.

The foregoing modification is illustrated as embodying a cowl bridge that is built in during the construction of the boat. The present invention may be adapted to existing boats, or boats without cowls, by a preferred embodiment as shown in Figure 4. By this arrangement, a bridge 15 may be secured athwartship by bolts 17 to the ribs 16 of the boat. The bridge 15 may be centrally slotted at 22 to provide two vertically spaced portions 15A and 15B that are respectively provided with vertical axially aligned bores 18A and 18B which are centrally of said bridge. A bolt or screw 19 is secured to the keel 1 with its head

18 embedded in the keel and a nut 20 locking said bolt to the keel. The bolt 18 extends up through said bores 18A and 18B and a hand wheel or nut 21 is threaded on said bolt 18 and disposed within the bridge slot 22. The hand wheel 21 reacts against the bridge portions 15A and 15B when it is threaded along the bolt to raise or lower the bolt and thereby bow the keel upwardly or downwardly.

In the operation of the boat, with my new and improved keel aligning device, the alignment of the keel, and consequently the elevation of the nose or bow of the boat relative to the water line, may be selectively varied simply by adjusting the turnbuckle 14 or the hand wheel 21 while the boat is in operation.

I do not wish to be limited to the exact mechanical structure, as other mechanical embodiments may be substituted still coming within the scope of my claims.

That which I claim as new, is:

1. In a boat having a normally relatively flat keel portion, a bridge spanning the bottom of said boat in its central portion and transversely above the keel portion, the central portion of said bridge being slotted to provide two vertically spaced portions, said bridge portions having vertical axially aligned bores therethrough centrally of said bridge, a screw fixed to the keel portion and extending upwardly through said bridge bores, and a nut on the screw and within the bridge slot for varying the relation of the screw to the bridge to bow the keel upwardly or downwardly relative to its normal flat position.

2. In a boat having a normally relatively flat keel portion, a bridge spanning the bottom of the boat in its central portion and transversely of the flat keel portion, the central portion of said bridge being spaced above said keel portion, a single rigid member secured to said keel portion substantially intermediate the ends of said keel portion and engaging said bridge, and a manually operable means carried by said rigid member cooperating with said bridge for varying of the length of the rigid member to bow the keel portion upwardly or downwardly relative to its normal flat position.
